BILLET GRINDING APPARATUS

Alfred E. Hamilton, Pittsburgh, Pa.

Application December 4, 1953, Serial No. 396,282

8 Claims. (Cl. 51—33)

My invention is particularly suitable for use in the 15 grinding of steel billets, but can, of course, be used in grinding articles of other shapes and materials. My invention is a modification of the structure shown in my Patent No. 2,442,042.

One object of my invention is to provide a simplified 20 form of apparatus for grinding the opposite faces of billets with uniformity, even though the sides to be surfaced do not extend in true planes or straight lines.

Another object of my invention is to provide improved 25 means for mounting grinding wheels that are oppositely disposed to one another; which are yieldably urged toward one another against opposite sides of a work piece, and which are provided with a common stop device which limits the distance which they may move toward each other independently of deviations of work piece surfaces.

Still another object of my invention is to provide an 30 improved manner of imparting vertically reciprocable movements to a grinding wheel (or a pair of grinding wheels) while in operative engagement with the sides of work pieces, while constantly rotating the grinding wheel and for simultaneously imparting tilting movements to the grinding wheel about a vertical axis that is transverse to the axis of rotation of the wheel.

As shown in the accompanying drawings, Figure 1 is 35 a vertical cross sectional view of the grinding apparatus of Fig. 3;

Fig. 2 is a view showing apparatus for conveying the billets one-by-one to the feed rolls for the machine;

Fig. 3 is a view taken on the line III—III of Fig. 1;

Fig. 4 is a partial plan view of certain of the feed rolls 40 of Fig. 3;

Fig. 5 is an enlarged side view of the ratchet feed mechanism of Fig. 3;

Fig. 6 is a view of that portion of the machine as shown 45 in Fig. 1, whereby oscillation of the grinding wheels is effected, and

Fig. 7 shows a manner in which the billets may be automatically given a quarter turn when passing from one 50 grinding machine to the next machine.

As shown more clearly in Fig. 2, billets 10 are conveyed 55 one-by-one by a conveyor 11 to a feed table 12 that rotatably supports feed rollers 13 which advance the billets to a feed roller 14 that is intermittently rotated by a pawl 15 whose teeth engage teeth of a ratchet wheel 15a on a shaft 16 to which the roller 14 is secured. The pawl 15 (Fig. 5) is pivotally mounted on a crank arm 17a that is oscillated by a rocker arm 17 pivotally mounted on the feed table. Downward movement of the rocker 17 under the action of gravity is limited by an adjustable stop screw 18.

When the free end of the rocker arm 17 is raised as will be hereinafter described, it will cause the pawl 15 to rotate the feed roll 14 one step. Whether this step is for a one-tooth pitch distance of the ratchet wheel, or more, depends upon the setting of the stop screw 18. The roll 14 has a sprocket drive connection 19 with the next succeeding feed roll 13, and the rolls 13 of the train of rolls

2

are all driven through similar sprocket chains 19, to thereby advance the billets to the grinding wheels. A spring-pressed roller 21 yieldably holds the billets snugly against the roll 14, a pair of springs 22 and adjusting screws 23 being provided above the bearings 24 of the roller 21, for this purpose.

A housing 25 that carries the bearings for the roller 21 has pairs of arms 26 and 27 secured thereto. A supporting roller 28 is journaled in the bracket arms 26, and a roller 29 is journaled on the arms 31 that are pivotally supported by the arms 27. The roller 28 serves to vertically support the billet as it passes the feed roll 14, and the roller 29 serves as a hold-down, urged by a spring 32, to steady the billets against chattering movements in vertical directions.

The billets are advanced step-by-step between a pair of grinding wheels 33 that are journaled in hanger arms 34 which, in turn, are pivotally supported at their upper ends upon a cross head 35 that moves along vertical slide-ways 35a. The grinding wheels are driven by electric motors 36 whose casings are rigidly connected to the hanger arms 34 and therefore will oscillate along with the hanger arms, about the pivots 37. Belt drives 38 are mounted on grooved pulleys for the grinding wheels and the motors respectively, the pulleys being of varying diameters so that the belts can be shifted from certain grooves to other grooves as may be required for changes in driving speed.

The grinding wheels are held against the work pieces 30 39 by a piston-and-cylinder arrangement at 39 to which air pressure is supplied through flexible hose connections 41. The cylinders at 39 are pivotally connected to the cross head 35, and their piston rods 42 are pivotally connected to the hangers 34.

The distance to which the grinding wheels may be moved toward one another by the pistons is controlled by a shaft 43 that has threaded connection with one of the hangers 34 and has a boss 45 that seats against the other hanger, so that the grinding wheels cannot be moved too far inwardly by their pistons, thus avoiding excessive grinding of the billets.

The cross head 35 is reciprocated vertically by an electric motor 46 that, through reduction gearing at 47, rotates a crank disc 48 which, through a link 49, is connected to a rocking lever 51 that is pivotally supported upon the top of the frame and is connected through links 52 to the cross head. The disc 48 is provided with a plurality of holes 53, whereby the link 49 can be connected thereto at adjusted positions, to thereby vary the length of vertical stroke of the cross head 35.

The billets are advanced step-by-step by upward movements of an arm 55 which is rigidly secured to the cross head 35 and has holes through which pull rods 56 and 57 extend, the two rods being connected by a chain or a cable 58 that extends over a pulley 59 which is journaled on a bracket that is carried by the frame of the machine. The rods 56 and 57 have knobs 60 and 61, respectively, adjustable thereon, so that when the cross head upon its down stroke, for moving the grinding wheels downwardly along the vertical faces of the billet 10, the bar 55 can engage the knob 61 to pull the lever 17 upward and cause the pawl to advance the feed rolls 16 one step. This brings an unpolished portion of the billet between the grinding wheels, which portion will be ground upon the next upward stroke of the cross head. This upward stroke may result in the knob 60 being raised by the bar 55 to again lift the lever 17 and operate the pawl for another slight advance of the billet, thereby again presenting unground surfaces for engagement with the grinding wheels on their next down-stroke.

Either of the knobs 60—61 can be so set that it will not be engaged by the arm 55, so the billet will be ad-

vanced only one step during a cycle of up and down movement of the cross head.

In order to give a slight rocking movement to the grinding wheels, thereby insuring better uniformity of grinding and reducing tendency of the abrasive surfaces to become "loaded," I mount a guide plate 63 on bracket bars 64 that are secured to vertical frame members 65. The plate 63 has an inclined slot 66 through which the adjusting shaft 43 extends. Since the shaft has threaded engagement with one of the hangers 34 and extends through a hole in the other hanger 34, the hangers and the shaft will be oscillated somewhat during vertical reciprocation of the cross head 35, thereby rocking the grinding wheels on the vertical faces of the work pieces, there being sufficient looseness at the cross head and the pivots 37 to permit of this.

As the billets pass the grinding wheels, they will be vertically supported by a roller 67 and will pass onto rollers 68 and beneath a hold-down roller 69 that corresponds to the roller 21. The rollers 68 can be driven by sprocket chains from the ratchet feed as are the rolls 13, or the work pieces can be simply advanced by the pushing force of succeeding work pieces as they leave the machine. Spray pipes 70 are provided for directing water against the grinding edges of the abrasive wheels, so as to avoid floating dust and grit particles.

Although the adjustments of the shaft 43 positively limit the distance to which the grinding wheels 33 may be moved toward one another, by their respective pistons and cylinder, there is, in effect, a floating support for the wheels, since their hangers 34 are pivotally supported on the cross head. By reason of this arrangement, the sides of a billet that may be warped somewhat will be more uniformly ground than if each hanger had a stop shoulder entirely independent of the other shoulder instead of the stop means (the screw thread and the shoulder 45) for both hangers being on the single shaft 43. The shaft 43 can be turned during operation of the machine to effect adjustments of the hangers 34 relative to each other. This is desirable because it permits of quick adjustments to compensate for wheel wear and changes in surface conditions of the billets passing through the machine, the operator thus being able to provide for proper grinding of the billets.

Also, the stop screw 18 can be adjusted during operation of the machine to vary the distance which the billets are moved at each step.

Since the machine of Figs. 1 and 3 grinds only two faces of the billets, I provide means such as the device of Fig. 7 for turning the billets one-fourth of a revolution, so that the other two faces of the billets will be in position for grinding at another station which will have grinding apparatus like that shown in Figs. 1 and 3.

A trough 70, which is an extension of the trough in which the rollers 68 are journaled has a shoulder 71 mounted therein that affords unbalanced support for the billets when they enter the trough 70, causing them to tip sidewise as in Fig. 7.

I claim as my invention:

1. Grinding apparatus comprising a vertically-reciprocable cross head, means for raising and lowering the cross head in continuously repeated cycles, a pair of hanger brackets pivotally supported by the cross head, a pair of motors and a pair of grinding wheels carried by the brackets, on parallel horizontal axes, each wheel being driven by one of the motors, in opposed relation to the other wheel, and means actuated step-by-step by the cross head, for advancing work pieces between the grinding wheels, in a direction parallel to their axes and in position for the grinding of opposite sides of said pieces.

2. Grinding apparatus comprising a vertically-recipro-

cable cross head, means for raising and lowering the cross head in continuously repeated cycles, a pair of hanger brackets pivotally supported by the cross head, a pair of motors and a pair of grinding wheels carried by the brackets, each wheel being driven by one of the motors, on a horizontal axis parallel to that of the other wheel, means for advancing the work pieces between the wheels along a path parallel to the wheel axes, and means for oscillating the grinding wheels about horizontal axes during the vertical movements of the cross head.

3. Grinding apparatus comprising a vertically-reciprocable cross head, means for raising and lowering the head in continuously recurring cycles, a hanger carried by the cross head, a grinding wheel rotatably supported on a horizontal axis by the hanger, a motor for driving the wheel, a feeding device for moving work pieces horizontally past the grinding wheel, means operated through vertical movements of the cross head for actuating the feeding device step-by-step, and means adjustable to effect said operation selectively, either upon the occurrence of the upward or the downward movements of the cross head, or during both of said movements.

4. Grinding apparatus as recited in claim 3, wherein means are provided for changing the length of each feeding step.

5. Grinding apparatus as recited in claim 3, wherein means are provided for changing the length of each feeding step, during operation of the machine.

6. Grinding apparatus comprising a vertically-reciprocable cross head, means for raising and lowering the head in continuously-repeated cycles, a hanger bracket pivotally connected at its upper end to the cross head, a motor carried by the bracket, a grinding wheel rotatably supported on the lower end of the bracket on an axis parallel to said pivotal connection and driven by the motor, means carried by the cross head for yieldably urging the lower end of the hanger and the grinding wheel in one direction, a work-supporting device that holds a work piece in position for engagement by the grinding wheel, during vertical movements of the cross head, and a guide member that swings the lower end of the hanger and the grinding wheel in a vertical plane that is parallel to the wheel axis.

7. Grinding apparatus comprising a vertically-reciprocable cross head, means for raising and lowering the cross head in continuously repeated cycles, a pair of hanger brackets pivotally supported by the cross head, a pair of motors and a pair of grinding wheels carried by the brackets, on parallel horizontal axes, each wheel being driven by one of the motors, in opposed relation to the other wheel, and means actuated step-by-step by the cross head, for advancing work pieces between the grinding wheels, in a direction parallel to their axes and in position for the grinding of opposite sides of said pieces, means for yieldably urging each wheel against one side of the work piece independently of the other wheel, and adjustable stop means between the hanger brackets for limiting movement of the wheels toward each other, to a predetermined relatively spaced distance.

8. The apparatus as recited in claim 7, wherein said stop means are adjustable during operation of the machine.
